UNITED STATES PATENT OFFICE.

WILLIAM GEORGE BEATTY, OF FERGUS, ONTARIO, CANADA.

WRINGER.

Application filed November 30, 1926. Serial No. 151,805.

My invention which relates to a wringer comprising adjustable means, having operative relation with the rolls for exerting pressure on them or inoperative relation with them for releasing the pressure, and driving means having operative relation with the rolls for their rotation or inoperative relation with them for the stoppage of their rotation is provided with means for simultaneously controlling the action of both the pressure exerting means and the driving means.

Various modifications in the structural details of the wringer are within the scope of the invention, and in the apparatus which I have made the wringer is constructed with a cover part which includes a pressure exerting spring or springs secured in operative or pressure exerting relation with the rolls by the movement of a sliding locking bar in one direction or released from pressure exerting relation with the rolls by the movement of the locking bar in the opposite direction. The driving means consist of a driving shaft provided with a driving bevel gear wheel and a driven shaft provided with two driven bevel gear wheels selectively movable into and out of mesh with the driving gear wheel. An operable control is provided for the driven gear wheels which is actuated by the locking bar to bring these driven gear wheels to a neutral position with the driving gear wheel when the locking bar is moved to release the cover part for relieving the pressure on the rolls.

For an understanding of my invention reference is to be had to the following description and accompanying drawings, in which:

Fig. 1 is a fragmentary vertical sectional elevation of a wringer constructed according to this invention, showing the driving means and the means for controlling the action of the pressure exerting means and the driving means,

Fig. 2 is a plan view of the wringer and driving head,

Fig. 3 is a side elevation of the wringer and driving head shown in Fig. 2,

Fig. 4 is a sectional elevation of the wringer shown in Figs. 2 and 3, and

Fig. 5 is a perspective view of the control for the driving mechanism.

Like characters of reference refer to like parts throughout the specification and drawings.

The wringer 25 is bolted or otherwise fas-

tened to the driving head 1, which may be of any appropriate shape and dimensions suitable for the purposes for which it is designed. In the construction shown in the drawings this driving head comprises a housing, substantially rectangular in cross-section and of a length greater than its depth or width. At two of the opposite sides of the housing are two horizontally disposed bearings 2, 2^a, the axes of which are in horizontal alignment. Slidably and rotatably journaled in the bearings are the arbors 3, 3^a, for the bevel gear wheels 4 and 5. The arbors 3, 3^a, are bored and the driven shaft 6 is mounted in their bores. The bevel gear wheels 4 and 5 are keyed or otherwise secured to the shaft for causing its rotation, when motion is imparted to either one of the bevel gear wheels. Loosely encircling the shaft between, and engaging, the bevel gear wheels 4 and 5 is a sleeve 7 and attached to or forming part of the sleeve 7 is a plate 8 having an elongated slot 9. Journaled at the top of the driving head is a mandrel 10 and fixed to the mandrel is a disc 11, the center of which is eccentric to the axis of the mandrel. Extending from the disc 11 is a pin 12 the axis of which is eccentric to the center of the disc and this pin is entered in the slot 9. At the outer end of the mandrel 10 is the wringer reverse lever 13 for rotating the mandrel, eccentric disc and pin.

The rotation of the disc 11 and pin 12 shifts the sleeve 7, and shaft 6 axially to bring the bevel gear wheel 4 or 5 into and out of mesh with the driving bevel gear wheel 14. The driving shaft 15, which is rotated by motion transmitted from any suitable source of power, is enclosed in a vertical standard 16 and the arbor 17 of the bevel gear wheel 14 is entered through an aperture 18 in the bottom side of the housing to extend below the driving head and into the upper end of the standard to receive the upper end of the driving shaft. The driving shaft is entered in a rectangular socket in the arbor 17 for causing the rotation of the bevel gear wheel 14 during the revolution of the shaft. On the outer side of the bottom of the housing or driving head is a boss 19, in which is entered and which snugly fits the upper end of the standard, for the assembly of the driving head on the standard. This construction provides for the rotatable adjustment of the driving head and wringer.

In the upper end of the standard 16 are a

plurality of keepers 20 which may take the form of apertures or indentations, and in the present construction these keepers 20 consist of notches extending downwardly into the 5 standard from its top edge. Slidably entered through the boss 19^a is a locking bolt 21 for engagement with any one of the keepers 20, for effectively but releasably securing the driving head and wringer in their selected 10 rotatable adjustment and connected to the locking bolt 21, for its actuation, is a rod 22 which extends from the locking bolt to the opposite side of the wringer 25.

For the attachment of the wringer to the 15 driving head 1, a plate 24 is integrally formed with the bearing 2^a and the main frame 25 of the wringer is bolted or otherwise secured to this plate. The wringer roll 26 is journalled in the main frame 25 at or near the bottom of 20 the wringer and the shaft 27 of the wringer roll extends through the main frame into the bearing 2^a. Pinned to the shaft 27 is a clutch member 28 which extends from the shaft a distance greater than the length of movement 25 of the bevel gear wheels 4 and 5. The shaft 6 is formed with a clutch member 29 which enters, or engages with, the clutch member 28, for causing the rotation of the shaft 27 and wringer roll 26, as the shaft 6 revolves. To 30 accommodate the clutch members 28 and 29, the bore of the arbor 3^a is enlarged, as shown at 30, and this enlargement extends inwardly from the end of the arbor to the inner end of the clutch member 29. When the bevel 35 gear wheels 4 and 5 are adjusted to move the bevel gear wheel 5 into mesh with the driving bevel gear wheel 14, as shown in full lines in Fig. 1, and the bevel gear wheel 4 out of mesh with it, as shown in full lines in the 40 same figure, motion is transmitted from the bevel gear wheels 14 and 5 and shaft 6 to the wringer roll 26 by means of the clutch members 28 and 29, and the wringer roll is rotated in one direction. During this adjustment of the bevel gear wheels the clutch member 29 moves partly out of the clutch member 28, but not sufficiently to disengage the clutch members. When the bevel gear wheels 4 and 5 are adjusted to move the bevel gear wheel 45 4 into mesh with the driving bevel gear wheel 14, and the bevel gear wheel 5 out of mesh with it, the rotation of the wringer roll 26 is reversed. When the bevel gear wheels 4 and 5 are moved to a neutral position, as 50 shown in dotted lines Fig. 1, neither of them is in mesh with the bevel gear wheel 14, and the rotation of the wringer roll 26 is then stopped.

The wringer and driving mechanism for 60 the wringer rolls are unitedly movable with the driving head and the operation of the wringer is not interrupted by the rotatable adjustment of the driving head and wringer.

Journalled in the main frame 25 of the 65 wringer is a wringer roll 31 and bearing on

the journals of this roll are pressure, or journal, blocks 32. Hinged to the top of the main frame 25 is the cover 33 provided with a down-turned flange 34, and extending through the flange 34 are two supporting members 35, the axes of which are parallel with the journals of the roll 31. Within the cover 33 is a leaf spring 36, the ends of which loosely rest on the supporting members 35 and have vertical movement in an upward 70 direction but their movement in a downward direction is limited by their engagement with the bolts. Centrally journalled in the top of the cover is the axle 37 of a rotatable cam or eccentrically mounted disc 38, and fitted 80 on the end of the axle, beyond the cover 33, is a crank 39. The disc continuously engages the spring 36 and is rotated to vary the tension of the spring. The pressure blocks 32 extend above the supporting members 35 85 when the cover is in a closed position and normally lift the spring from the supporting members, so that when the cover is closed and secured in its closed position, the spring is at all times in pressure exerting relation with the blocks and by means of the latter with the wringer rolls. When the disc 38 is rotated to the position shown in dotted lines in Fig. 4, the spring 36 is tensioned to the minimum degree and when the disc is turned 90 to the position shown in full lines in Fig. 4, the spring is tensioned to the maximum degree.

This construction provides a simple and rapid adjustment for correctly varying the 100 pressure on the rolls.

The disc 38 is rotated slightly beyond its central position when applying the maximum pressure of the spring, and the crank 39 then moves to the position shown in full lines in Fig. 4 and engages the cover 33. The disc is prevented from inadvertently moving from this position in one direction and releasing the pressure during the operation of the wringer rolls, by the engagement of the crank 39 with the cover, and is prevented from inadvertently moving in the other direction by its engaging relation with the spring and by the weight of the crank.

Other types of springs and tension devices 115 may be employed in lieu of the specific type shown and described and it is not intended that the invention should be limited to this specific construction.

The cover, including the pressure exerting 120 means, are for convenience, termed the cover part, and for holding the cover part in operative relation with the wringer rolls, a locking bar 40 is reciprocatingly attached to the main frame 25. This locking bar is formed with elongated slots 41 through which are entered headed bolts or studs 42 projecting from the main frame 25, for slidably securing the locking bar to it and for guiding the locking bar during its reciprocating move- 125 130

ment. The locking bar is provided with two hooks 43 spaced to come into engagement with two projections 44 on the cover 33, and by their engagement with the projections, 5 securely lock the cover in its closed position and maintain the spring in pressure exerting relation with the rolls. The hooks on the locking bar are comparatively long and so shaped that they draw the hinged cover down 10 to its locked position and transfer the pressure of the spring from the supporting members 35 to the pressure blocks 32.

At the bottom of each hook 43 is a slight recess into which the projections 44 drop 15 when the locking bar is moved to the limit of its locking position, for preventing the hooks from inadvertent displacement from the projections 44. Extending horizontally from the locking bar is a lug 45 formed with 20 a slot 46 through which is entered a wringer release lever 47, the lower end of which is fulcrumed at 48 to the main frame 25. The actuation of the lever 47 operating through the slot 46 effects the movement of the locking bar for the engagement of the hooks 43 with the projections 44 and for the release of 25 the hooks from them. The release of the locking bar from the projections immediately releases the pressure of the cover part on the 30 wringer rolls. This release of pressure does not, however, in the case of accident, for example if an article of clothing is winding on the lower roll, correct the trouble and to do so it is necessary that the rotation of the 35 rolls should be stopped. Heretofore it has been customary to effect this stoppage by an additional operation which necessarily causes confusion and loss of time. To avoid this confusion and loss of time, the locking bar 40 40 is formed with an arm 49 pivotally connected with a reversing lever control 50. This control takes the form of a forked link having two projections 52 which engage cam shaped lugs 53 extending laterally from the wringer 45 reverse lever 13. The control 50 has a sliding action on the top of the driving head or housing 1, and the locking bar, when moved to its operative position for the engagement of the hooks 43 with the projections 44, pushes 50 the control 50 in the direction of arrow (Fig. 5). The forks 54 of the control 50 are located one at each side of the mandrel 10 and the space between the forks is sufficient to enable them to freely pass the mandrel and the hub 55 55 of the wringer reverse lever 13 as the control moves during its actuation. The projections 52 are placed at or near the ends of the forks 54 and when the control is pressed to the limit of movement in the direction of 60 arrow (Fig. 5) the projections 52 are entirely free from contact with the cam shaped lugs 53. The wringer reverse lever 13 can then be rotated manually to selectively move either of the bevel gear wheels 4 or 5 into 65 mesh with the bevel gear wheel 14, or to

bring the bevel gear wheels 4 and 5 to a neutral position without imparting movement to the locking bar.

In this way the driving mechanism can be controlled for the rotation, reversing, and 70 stoppage, of the wringer rolls without actuating the locking bar to release the cover and without interfering with the pressure exerted by the spring.

In the event of accident, the pressure exerted on the wringer rolls can be instantly released by moving the locking bar 40 to disengage the hooks 43 from the projections 44, and the locking bar, during this release of pressure, moves the control 50 in the opposite 80 direction to the arrow shown in Fig. 5, and brings the projections 52 into engagement with the lugs 53 irrespective of the position of the wringer reverse lever 13 when the control is actuated. The engagement of the projections 52 with the lugs 53 during the continued action of the locking bar, rotates the wringer reverse lever 13, mandrel and eccentric disc, to the position shown in Fig. 5, and this rotation of these parts brings both the 85 bevel gear wheels 4 and 5 to the neutral position of the driving mechanism, in which position neither of the bevel gear wheels 4 and 5 is in mesh with the bevel gear wheel 14 and no driving motion is transmitted to the 90 wringer roll 26. The actuation of the control 50 is simultaneous with the actuation of the locking bar 40 to release the cover part and consequently the rotation of the wringer rolls is stopped immediately the pressure 95 exerted on the rolls is relieved.

Having thus fully described my invention what I claim as new and desire to secure by Letters Patent is:

1. A wringer comprising a set of rolls, a 105 cover part including a spring for exerting pressure on the rolls, driving means for rotating the rolls, and a reciprocatory locking bar for securing the cover part and maintaining the spring in its pressure exerting relation with the rolls, said reciprocatory locking bar having operable connection with the driving means and when actuated to release the pressure of the spring on the rolls simultaneously controlling the action of the driving 110 means for the stoppage of the rotation.

2. A wringer comprising a set of rolls, a cover part including a spring for exerting pressure on the rolls, driving means for rotating the rolls, a control for the driving means, 120 and a reciprocatory locking bar for securing the cover part and maintaining the spring in its pressure exerting relation with the rolls and actuating the control for the stoppage of the rolls simultaneously with the release of 125 pressure.

3. A wringer comprising a set of rolls, a cover part including a spring for exerting pressure on the rolls, driving means for the rotation of the rolls, and a reciprocatory lock- 130

ing bar for securing the cover part and maintaining the spring in its pressure exerting relation with the rolls and having operable connection with the driving means, said reciprocatory locking bar when actuated simultaneously releasing the pressure of the spring and stopping the rotating action of the driving means.

4. A wringer comprising a set of rolls, a cover part including a spring for exerting pressure on the rolls, driving means for the rotation of the rolls, a control for the driving means, and reciprocatory means for releasably securing the cover part and maintaining the spring in its pressure exerting relation with the rolls, said reciprocatory means when actuated to release the cover part simultaneously actuating said control for the stoppage of the driving means.

5. A wringer comprising a set of rolls, a cover part, including a spring for exerting pressure on the rolls, driving means for the rotation of the rolls, a reciprocatory locking bar for securing the cover part and maintaining the spring in its pressure exerting relation with the rolls, and means actuated by the locking means, when reciprocated to release the cover part, for stopping the rotating action of the driving means.

6. A wringer comprising a set of rolls, a cover for the wringer, a spring mounted in the cover for exerting pressure on the rolls when the cover is locked in its closed position, driving means for the rotation of the rolls, reciprocatory means for locking the cover and securing the spring in pressure relation with the rolls and having operable connection with the driving means, said reciprocatory means simultaneously stopping the rotation of the rolls when actuated to release the cover.

7. A wringer comprising a set of rolls, a cover for the wringer, a spring carried by the cover for exerting pressure on the rolls when the cover is locked in its closed position, a driving gear wheel, a shaft having operable connection with the rolls, two driven gear wheels adjustable on and rotatable with the shaft and selectively movable into and out of mesh with the driving gear wheel, control means for adjusting the driven gear wheels, and reciprocatory locking means for securing the cover in its closed position and the spring in pressure exerting relation with the rolls, said locking means having operable connection with the control means for moving the driven gear wheels out of mesh with the driving gear wheel when it is actuated to release the cover.

8. A wringer comprising a set of rolls, a cover part, including a spring for exerting pressure on the rolls, a shaft having operable connection with the rolls for their rotation, a driving gear wheel, two driven gear wheels adjustable on and rotatable with the shaft, control means for moving the driven gear

wheels to a neutral position with relation to the driving gear wheel or selectively bringing either of the driven gear wheels into mesh with it, a lever for the control means, and reciprocatory locking means for securing the cover part and maintaining the spring in pressure exerting relation with the rolls, said locking means, when operated to release the cover part actuating the control lever for moving the driven gear wheels to a neutral position for the stoppage of the rolls.

9. A wringer comprising a set of rolls, a cover part including a spring for exerting pressure on the rolls, adjustable driving means for rotating the rolls, a reciprocatory locking bar for securing the cover part and maintaining the spring in pressure exerting relation with the rolls during their rotation, a control for the driving means, and an operable connection between the locking bar and the control, said locking bar, when operated to release the pressure of the spring, actuating the driving mean for the stoppage of the rolls simultaneously with the release of the pressure.

10. A wringer comprising a set of rolls, a cover part provided with spring means for exerting pressure on the rolls, a driving gear wheel, a shaft having operable connection with the rolls, two gear wheels adjustable on and rotatable with the shaft and movable into and out of mesh with the driving gear wheel, control means for moving the driven gear wheels out of mesh with the driving gear wheel or selectively bringing either of the driven gear wheels into mesh with it, a lever for actuating the control means, cam shaped lugs projecting from the lever, a reciprocatingly movable link having projections engaging said lugs, and locking means, for securing the cover part and maintaining the spring in pressure exerting relation with the rolls, said locking means having connection with the link and when operated simultaneously releasing the cover part and actuating the control means to move the driven gear wheels to a neutral position.

11. In a wringer the combination of a set of rolls, a driving gear wheel, two driven gear wheels, movable alternatively into mesh with the driving gear wheel, for the rotation of the rolls, and out of mesh for the stoppage of the rotation, a spring for applying pressure to the rolls, and reciprocatory movable means having operable relation with the gear wheels and spring, said reciprocatory means holding the spring in its pressure exerting relation with the rolls during their rotation, and when reciprocated for releasing the pressure simultaneously moving the meshed driven gear wheel out of mesh with the driving gear wheel for the stoppage of the rotation.

12. In a wringer the combination of a set of rolls, a driving gear wheel, two driven

- gear wheels, movable alternatively into mesh with the driving gear wheel, for the rotation of the rolls, and out of mesh for the stoppage of the rotation, a spring for applying pressure to the rolls, and a reciprocatory locking bar having operable relation with the gear wheels and spring, said bar holding the spring in its pressure exerting relation with the rolls during their rotation, and releasing the pressure and simultaneously moving the meshed ¹⁰ driven gear wheel out of mesh with the driving gear wheel for the stoppage of the rotation.
- Dated at the town of Fergus, in the county of Wellington and Province of Ontario, this ¹⁵ 30th day of October, 1926.

WILLIAM GEORGE BEATTY.
